CARRYALL PURSE FOR RING BINDERS

Irving Rubinstein, New York, N. Y.

Application January 24, 1956, Serial No. 39,896

Term of patent 7 years

(Cl. D87—3)

Fig. 1

Fig. 3

Fig. 1 is a front perspective view of a carryall purse for ring binders, showing my new design;

Fig. 2 is a rear view in elevation thereof; and

Fig. 3 is a side elevational view thereof.

I claim:

The ornamental design for a carryall purse for ring binders, substantially as shown.
